DESIGN FOR A SHOE HEEL

William H. Cary, Brockton, Mass., assignor to
Avon Sole Company, Brockton, Mass., a corpora-
tion of Massachusetts

Application March 5, 1941, Serial No. 99,367

Term of patent 14 years

To all whom it may concern:

Be it known that I, William H. Cary, a citizen of the United States, residing at 45 Fairview Avenue, Brockton, in the county of Plymouth and Commonwealth of Massachusetts, have invented a new, original, and ornamental Design for a Shoe Heel, of which the following is a specification, reference being had to the accompanying drawing, forming a part thereof.

In the drawing,

Fig. 1 is a perspective view of a shoe heel showing my new design.

Fig. 2 is a plan, being a bottom view; and

Fig. 3 is a sectional view along the line 3—3 of Fig. 2.

I claim:

The ornamental design for a shoe heel, substantially as shown.

WILLIAM H. CARY.
